UNITED STATES PATENT OFFICE.

ANTOINE B. MACKENZIE, OF TOLEDO, OHIO.

DESIGN FOR A HAND-MIRROR.

41,553.

Specification for Design. Patented July 11, 1911.

Application filed April 14, 1911. Serial No. 621,158. Term of patent 7 years.

To all whom it may concern:

Be it known that I, ANTOINE B. MACKENZIE, a citizen of the United States, residing at Toledo, in the county of Lucas and State of Ohio, have invented a new, original, and ornamental Design for Hand-Mirrors, of which the following is a specification, reference being had to the accompanying drawings, forming part thereof.

In the drawings Figure 1 is a face view and Fig. 2 a side view of a hand mirror showing my new design.

I claim:

The ornamental design for a hand mirror, substantially as shown.

ANTOINE B. MACKENZIE.

Witnesses:

C. W. OWEN,
E. E. THOMAS.
